CLAIM

The ornamental design for the pouch for a portable audio unit, as shown and described.

DESCRIPTION

FIG. 1 is a perspective view of the present invention;
FIG. 2 is a side view of the present invention;

FIG. 3 is a top view of the present invention;

FIG. 4 is a front view of the present invention;

FIG. 5 is a bottom view of the present invention;

FIG. 6 is a back view of the present invention;

FIG. 7 is another side view of the present invention;
FIG. 8 is a section view of the present invention taken
at 8—8 of FIG. 1; and,

FIG. 9 is another perspective view of the present invention.
